(57) **CLAIM**

The ornamental design for an MX goggle, as shown and described.

DESCRIPTION

Related patents and applications owned by Applicants:
U.S. Design Pat. No. D60,184S

U.S. Design patent application for Snow Goggle Design
being filed concurrently with this application.

U.S. Utility patent application entitled “Goggles, Eyewear
and Marks with Adjustable Input Devices” filed on Jan. 6,
2013.

FIG. 1 is a front perspective view of an MX goggle showing
our present invention;

FIG. 2 is a top plan view of the MX goggle of FIG. 1.

FIG. 3 is a front elevational view of the MX goggle of FIG. 1.

FIG. 4 is a rear elevational view of the MX goggle of FIG. 1.

FIG. 5 is a left side elevational view of the MX goggle of FIG.
1.

FIG. 6 is a right side elevational view of the MX goggle of
FIG. 1; and,

FIG. 7 is a bottom plan view of the MX goggle of FIG. 1.
